US00D878305S

(12) **United States Design Patent** (10) **Patent No.:** **US D878,305 S**
(45) **Date of Patent:** **** Mar. 17, 2020**

(54) **SEALING SHROUD**

(71) Applicant: **Molex, LLC**, Lisle, IL (US)

(72) Inventors: **Duy Nguyen**, Chicago, IL (US);
Anthony Gerard Quebbemann,
Lisbon, WI (US)

(73) Assignee: **Molex, LLC**, Lisle, IL (US)

(**) Term: **15 Years**

(21) Appl. No.: **29/618,982**

(22) Filed: **Sep. 26, 2017**

(51) LOC (12) Cl. **13-03**
(52) U.S. Cl. **USPC D13/156**

(58) **Field of Classification Search**

(57) **CLAIM**

The ornamental design for a sealing shroud, as shown and described.

DESCRIPTION

FIG. 1 is a front perspective view of a sealing shroud showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a front perspective view of the sealing shroud of FIGS. 1-6 shown in a second state;

FIG. 8 is a front view thereof;

FIG. 9 is a rear view thereof;

FIG. 10 is a right side view thereof;

FIG. 11 is a left side view thereof;

FIG. 12 is a top view thereof;

FIG. 13 is a front perspective view of the sealing shroud of FIGS. 1-6 shown in a third state;

FIG. 14 is a front view thereof;

FIG. 15 is a rear view thereof;

FIG. 16 is a right side view thereof;

FIG. 17 is a left side thereof; and,

FIG. 18 is a top view thereof.

The broken line showing of the remainder of a connector assembly represents unclaimed environmental subject matter and forms no part of the claimed design.

1 Claim, 18 Drawing Sheets
